UNITED STATES PATENT OFFICE.

WALTER K. MILNE, OF BROOKLYN, NEW YORK.

EYE-SHADE.

1,401,118.

Specification of Letters Patent. Patented Dec. 20, 1921.

Application filed June 3, 1921. Serial No. 474,680.

To all whom it may concern:

Be it known that I, WALTER K. MILNE, a citizen of the United States, and a resident of the city of New York, borough of Brooklyn, in the county of Kings and State of New York, have invented a new and Improved Eye-Shade, of which the following is a full, clear, and exact description.

This invention has relation to protective devices for the eyes and refers more particularly to an eye shade, the primary object in view being to produce an extremely simple and cheap article of manufacture of this character which consists of independent shade members adapted to be respectively positioned in shading relation to each eye and supported from the bridge of the nose.

The invention further contemplates the provision of an eye shade which is preferably, but not necessarily, constructed from a single piece of semi-transparent resilient material which is light and comfortable, and which is sufficiently small in size to render the same capable of being worn beneath a pair of glasses or spectacles.

A further object in view resides in the provision of an eye shade of the character described which is self adjusting to snugly fit above the eye without the employment of expensive adjusting devices.

A further object in view resides in the provision of an eye shade which is highly efficient in its purpose, strong and durable in construction, and which is of a convenient size to permit of the carrying of the same on the person of the wearer when not in use.

With the above recited and other objects in view, some of which will appear more clearly as the nature, purpose and use of the invention is better understood, reference is had to the following specification, the appended claims and the accompanying drawings, in which—

45 Figure 1 is a perspective view illustrating the eye shade in its applied position.

Fig. 2 is a top plan view of the same removed.

Fig. 3 is a front elevation thereof.

50 Fig. 4 is a plan view of the blank from which the shade is formed prior to the bending and fashioning of the same.

Referring to the drawings by characters of reference, 10—10 designate a pair of individual identically formed shade members, and 11 a bridge or nose piece con-

nected the same and serving to engage with the bridge of the nose for properly positioning and supporting the shade members relative to the eyes for shading the same. 60

Preferably the shade members and bridge are formed from a single or integral piece of material of a semi-transparent resilient nature such as celluloid or the like. The shade members are preferably disposed at 65 an angle relative to the bridge, said bridge being provided with a reduced neck 12 at its juncture with each shade member. The lower edge 13 of each shade member is curved upwardly and the upper edge 14 is substantially 70 straight.

To fashion the shade in its finished form, the bridge or nose piece is bent in substantially circular form and each of the shade members 10 are bent in substantially semi-conical form, the necks 12 being designed to be arranged in substantially parallel confronting relation. The free outer extremities of each of the shade members are bent or curved outwardly as at 15 for a purpose 80 to be hereinafter set forth.

In use of the device the bridge 11 is pinched on to the bridge of the nose, the necks 12 engaging the opposite sides thereof, the inherent resiliency of the material from 85 which the device is constructed serving to frictionally maintain the upper edges 14 in close contact with the face of the wearer immediately below the eyebrows, while the curved outer extremities 15 engage and coact 90 with the upper portion of the cheek bone at the outer corner of the eye. By this arrangement the shade members 10 are positioned to effectively shade the eyes of the wearer and the small size of the whole device 95 permit of the wearing of glasses or spectacles over the same when necessary. Normally when the eye shade is detached and not in use, the inherent resiliency of the same effects the swinging of the shade members 10 100 into opposed relation as illustrated in Figs. 2 and 3. In applying the shade, the curved extremities 15 are grasped to spread the shade members 10 apart, and the bridge piece 11 is forced into position on to the 105 bridge of the nose, the resiliency of the material causing the upper edges 14 of the shade members to snugly fit and engage the face directly below the eyebrow, the curved outer ends as heretofore explained contact- 110 ing with the face adjacent the outer corners of the eyes.

While there has been illustrated and described a single and preferred embodiment of the invention, it is of course to be understood that the same is subject to various 5 modifications and changes, and it is to be understood that the right is reserved to other embodiments which properly fall within the scope of the appended claims.

Having thus described my invention, what 10 I claim is:

1. As an article of manufacture, an eye shade comprising two shade members each of which extends over the eye to a point adjacent the outer corner of the same, and a 15 bridge piece having a resilient connection with the shade members, whereby the whole is rendered self-adjusting and the shade members held in juxtaposition to eye brows of the wearer throughout their entire length.
2. As an article of manufacture, an eye shade comprising a nose bridge, two long curved shade members with their outer extremities extended to contact with the cheek 20

bones at the outer corners of the eyes, and two narrow neck pieces secured to the bridge 25 piece and shade members, said bridge serving to frictionally engage the nose for support, and said neck pieces serving, owing to their resiliency, to make the whole automatically self-adjusting and to press the 30 upper edges of the shade members throughout their length into contact with the face of the wearer thus screening out all light from the upper half of the visual angle.

3. As an article of manufacture, an eye 35 shade constructed from a single strip of resilient material and formed to provide individual shade members, and a nose bridge, the shade members and bridge being connected by necks, whereby the shade members 40 are maintained in juxtaposition to the eyes with the ends thereof in engagement with the cheek bones at the outer corners of the eyes.

WALTER K. MILNE.
